UNITED STATES PATENT OFFICE.

JENS A. PAASCHE, OF CHICAGO, ILLINOIS.

PNEUMATIC PAINT-BRUSH.

1,273,784.

Specification of Letters Patent. Patented July 23, 1918.

Application filed January 23, 1915. Serial No. 3,863.

To all whom it may concern:

Be it known that I, JENS A. PAASCHE, a citizen of the United States, residing at Chicago, in the county of Cook and State 5 of Illinois, have invented certain new and useful Improvements in Pneumatic Paint-Brushes, of which the following is a specification.

This invention relates to the air-brush art 10 and contemplates certain improvements which are herein shown as embodied in a brush of the type disclosed in my prior Patent No. 1,104,217, issued July 21, 1914, although certain features of the invention 15 are also applicable to other types of brushes.

One of the objects of the present invention is to improve the construction of the color-discharge means and the operating means therefor.

20 Another object has to do with the position and relation of the air-trigger to the color-trigger, whereby the air-valve may be unseated to discharge air for the purpose of dusting off the work without affecting the 25 color-discharge means.

A further object is to provide a brush 30 which is particularly adapted for applying materials in powder form, as in bronzing or like work, the brush being arranged to handle a powdered coloring material in conjunction with a liquid.

The invention also relates to color containers of improved construction and to the means for associating said containers with 35 the brush body.

Another object is to provide means whereby pressure may be placed upon the liquid paint material if desired, to assist in feeding said material.

40 Further objects relate to various details of construction which will be fully pointed out in the following description.

In the accompanying drawings, Figure 1 is a side elevation of a pneumatic paint 45 brush embodying the features of my invention. Fig. 2 is a side elevation of a brush having a different style of paint container associated therewith. Fig. 3 is a longitudinal central section through the brush, the 50 paint containers being omitted from this view. Figs. 4, 5 and 6 are detail views of three interchangeable sets of color-discharge

devices having different sized discharge orifices. Figs. 7 and 8 are respectively fragmental plan and sectional views illustrating 55 the hollow needle or tube which conveys the coloring material. Fig. 9 is an end view of the forward end of the brush. Figs. 10 and 11 are longitudinal central sectional views of the powder and liquid containers, respectively. Fig. 12 is a transverse sectional view through the body taken in the plane of line 12 of Fig. 1 and illustrating a part of the means for placing air pressure upon the liquid coloring material. 65

I will herein describe in detail the preferred embodiment of my invention which is shown in the drawings, without any intention, however, of limiting the invention itself to the construction disclosed, except 70 as recited in the appended claims.

The brush comprises a tubular body or barrel 15 which is tapered at its forward end and has at its tip an air nozzle 16. This nozzle is provided with a flaring guard or 75 extension to inclose and protect the tip of the paint discharge structure which projects thereinto. Secured to the rear part of the barrel is a downwardly extending handle 17 by which the brush is held in the hand 80 like a pistol. Ribs 18 on the handle provide spaces for the fingers so that a more effective and comfortable grip is afforded. The thickness of the rear edge of the handle is increased by vertical ribs 18^a for the sake 85 of comfort to the hand. 19 is a rod which is adjustably fixed in the handle by a screw 20 and provides a support or rest.

On the rear end of the barrel 15 is mounted a two-part structure or head 21 having 90 an air passage 22 therethrough, the inner end of which passage communicates with a pipe 23 which runs to the air nozzle 16. On the outer end of the head 21 is threaded a nipple 24 which is adapted to be surrounded by a flexible hose 25, leading to a suitable source of pressure fluid, as compressed air. A sleeve 26 surrounds the hose 25 and the nipple 24 and at its inner end is threaded onto the nipple, so that the 95 hose will be tightly compressed against the nipple to prevent its being expanded or forced off the nipple by the air pressure. 100

A valve member 27 in the passage 22 con-

trols the flow of air therethrough, said valve member being normally held against its seat by a spring 28 and having a stem 29 which is connected by means of a rod or link 30 with a trigger 31 positioned forwardly of the handle 17 and pivoted at its upper end at 32 in the barrel 15.

A lug 33 projects downwardly from the forward end of the body or barrel 15 and 10 supports a sleeve 34, the latter being secured in an opening in the lug by means of a set screw 35. On the forward end of the sleeve 34 is threaded a sleeve 36, within which are located the color needle 37 and nozzle 38. 15 The color needle or tube 37 is suitably fixed in the forward end of the sleeve 34 with their central openings in alinement. The forward end of the needle is tapered, and the internal passage thereof terminates 20 upon this tapered surface short of the extreme forward end of the needle. See Figs. 7 and 8. Preferably, the tapered portion of the needle is grooved or reduced in diameter to provide one or more shoulders 39 25 for the purpose of providing a tighter fit between the tapered portions of the needle and nozzle, so as to prevent leakage of fluid therefrom. The needle is also provided with a suitable number of annular grooves 30 40 located behind the tapered portion, the latter grooves being intended to receive a lubricant, preferably a very hard oil. This oil greases the interior of the nozzle and facilitates sliding the same, and the oil also 35 prevents any of the liquid-coloring material from working back between the needle and the nozzle and thus causing these parts to stick.

The nozzle 38 surrounds the needle 37 40 and is internally tapered at its forward end to fit against the tapered end of the needle. The nozzle fits loosely in the forward end of the sleeve and is slidable forward and back along the needle to open and close the 45 forward end of the needle passage so as to control the discharge of paint material therefrom. A coiled spring 41 surrounds the nozzle and bears at one end against an internal shoulder on the sleeve 36 and at its 50 other end against an annular shoulder or enlargement 42 on the nozzle, said spring tending to hold the nozzle in its rearward position to cut off the discharge of paint material.

55 As will be seen from the drawings, the discharge orifice 43 in the forward end of the nozzle 38 is somewhat elongated or elliptical in shape and opens partially toward one side of the nozzle, the orifice being disposed in a general plane oblique to the axis of the nozzle and approaching a parallel to the air stream issuing from said nozzle. In other words, the side of said discharge orifice which is closest to the orifice 60 of the air nozzle 16 is cut back away from

the forward end of the paint nozzle 38 and toward the said air orifice.

The stream of air issuing from the orifice in the air nozzle diverges, and the color discharge structure is positioned so that the tip 70 normally protrudes into this diverging air current. Thus when the nozzle 38 is slid forwardly, the oblique edge of the discharge orifice 43 therein will be carried well into the current of air. On account of the shape 75 of the discharge orifice and its relation to the air current, the latter will exert a maximum pull in drawing out paint from the nozzle 38, because the entire periphery of the discharge orifice is more accessible to 80 the current of air than it would be if the orifice were formed at right angles to the axis of the paint nozzle, as is the common construction. By the shape and relation of the parts described, a maximum efficiency 85 is obtained in which a given quantity of paint will be drawn out by the smallest amount of air.

The different coating materials which the brush is adapted to handle may vary in their 90 viscosity, and in order that the brush may operate with the greatest efficiency for different materials, a plurality of similar paint discharge structures composed of the parts 34, 36, 37, 38, and 41, are in practice furnished with each brush, the color nozzles 38 of the different structures having discharge orifices 43 which vary in size. Figs. 4, 5 and 6 illustrate three different paint discharge structures having nozzles 38, 38^a and 38^b provided with discharge orifices 43, 43^a and 43^b of different sizes. The flaring dotted lines indicate approximately the different 100 sizes of jets or sprays which will issue from these structures when open to full capacity. 105

The nozzle 38 is arranged to be moved forwardly to permit the discharge of color by means of a rod 44 within the barrel 15, the forward end of said rod passing through slots in the barrel and the sleeve 36 and engaging in a recess 45 in the enlargement 42 of the nozzle 38. The rear end of the rod 44 passes loosely through an opening in the air trigger 31 and is connected to the upper end of a secondary trigger 46 which is 110 mounted in this instance in a slot in the handle 17 and is pivoted on a removable pin or screw 47. The lower end of the trigger 46 is arranged to be engaged by the air trigger 31 when the latter is moved rearwardly so as to slide the rod 44 forwardly and thereby operate the color nozzle 38. It will be noted that by moving the trigger 31 rearwardly the rods 44 and 30 may be longitudinally moved in opposite directions. 115 In the normal position of the parts, the air trigger 31 is spaced a short distance away from the trigger 46 and said air trigger may be hollowed or concave at its rear side so that it may be drawn rearwardly 120 125 130

a short distance to open the air valve before the trigger 46 is engaged. Thus the stream of air issuing from the nozzle 16 may be utilized to blow off dust from the article to be coated, and when the paint nozzle is opened the paint will immediately be caught by the already flowing current of air. As soon as the triggers are released, the spring 41 moves the nozzle 38 rearwardly to immediately cut off the flow of paint without any attention or adjustment by the operator. Thus it is impossible for a quantity of paint to accumulate at the tip of the nozzle and there dry up and clog the outlets.

It is sometimes desirable in producing stipple effects to hold the paint nozzle partially projected or opened so that a constant or definite amount of paint may be drawn therefrom as soon as the air valve 27 is unseated and without operating the trigger 46 by the trigger 31. To this end I have provided an adjustable screw 48 seated in the handle 17, the tip of the screw being arranged to bear against the trigger 46 above its pivot 47, so as to hold the rod 44 and the paint nozzle 38 projected the desired distance. A transverse opening 49 through the handle receives the head of the screw 48 and gives access thereto for adjusting the screw.

When it is desired to substitute a paint discharge structure having a discharge orifice 43 of different size, the screw 48 is turned to withdraw it from behind the trigger 46, and the pivot screw 47 is removed, so that the trigger 46 may be pushed rearwardly to withdraw the rod 44 from the sleeve 36. Upon loosening the set-screw 35, the paint discharge structure may now be bodily removed from the opening in the lug 33. Another structure is then inserted in place in the lug and the parts associated as before.

The liquid paint material may be contained in a can 50 (Fig. 1) supported directly upon the brush or in a bucket 51 (Fig. 2) adapted to be supported upon an elevated shelf or the like. The bucket may have a valved fitting 52 thereon which is connected by a flexible hose 53 with a valved fitting 54 adapted to be attached to the rear end of the sleeve 34 of the paint discharge structure. The fitting 54 is preferably shaped so as to lie alongside the barrel 15, the end of said fitting being bent downwardly to engage the sleeve 34. This arrangement has been found to be the most convenient for the operator.

The can 50 has a fitting 55 rigidly secured to its lower end and communicating with its interior, the fitting having a valve 56 and being adapted to be rigidly attached to the rear end of the sleeve 34, the same as the fitting 54. The means for securing

either of these fittings to the sleeve 34 comprises an enlarged conical head 57 on the fitting (see Fig. 3) which is arranged to engage in the rear end of the sleeve, and an interiorly threaded nut 58 surrounding said head and adapted to be turned onto the threaded rear end of the sleeve to clamp the head thereto.

It will be noted that both the can 50 and the bucket 51 are located wholly above the paint discharge structure, so that a true gravity feed of the liquid material is obtained. This is found to be superior to the arrangement of paint containers heretofore employed, in which the containers were positioned below the paint discharge structure and the suction of the air was depended upon entirely to draw the paint material from the containers. The present brush is particularly adapted for use with materials of heavier or thicker consistency than those commonly used with air brushes, such for example, as ordinary house paints, lacquers, varnishes, etc., and a gravity feed is particularly desirable for such materials.

It is sometimes desirable to place additional pressure upon the material to assist in feeding the same and I have provided means for accomplishing this. The can 50 is provided with a friction tight cover 59 having a central stem 60 rigid therewith, the lower end of which is adapted to be threaded into a boss 61 on the bottom of the can, for firmly securing the cover in place. On the upper side of the cover is fixed a head 62 which is cupped on its upper side and from this cup a passage 63 leads through the stem 60 to the interior of the can. A flexible hose 64 has secured to one end a tapering head 65 arranged to engage in the cupped head 62 and to be secured therein by a surrounding nut 66 engaging exterior threads on said head 62. The other end of the hose 64 communicates with the air passage 22 in the structure 21 at the rear end of the barrel 15 so that air may be supplied to the interior of the can to replace pressure on the liquid therein. The flow of the air is controlled by a valved fitting 67 (Fig. 12) interposed between the air passage 22 and the hose 64, said fitting comprising a body having a passageway in which is formed a tapering valve seat arranged to coöperate with a needle valve member 68, whereby the flow of air may be entirely cut off or regulated as desired.

A can 69 adapted to receive a powdered coating material is positioned above the forward end of the body of the brush, being mounted in a bracket 70 which has one end detachably secured to the upper side of the barrel 15 as by a screw 71. The free end of said bracket is in the form of a ring 72 in which the can 69 is seated, being suitably held therein by means such as a set-screw 73.

The lower end of the can is conical or funnel-shaped and the ring 72 may be interiorly shaped to conform to the funnel portion of the can (see Fig. 10). The can is 5 provided with a friction tight cover 74 and to the inner side of this cover is rigidly secured one end of a sleeve 75, the lower end of said sleeve being threaded in a suitable cross-bar or spider 76 fixed in the lower portion 10 of the can. A rod 77 has a portion 78 threaded in the cover and the sleeve 75 and has a knurled head 79 fixed on its upper end outside of the cover, whereby the rod may be manually rotated. The lower end of 15 the rod is tapered as at 80 and constitutes a valve member adapted to coact with a tapered valve seat 81 formed on the upper end of a nozzle 82 which is threaded into the lower end of the funnel portion of the can 20 69. Above the tapered or valve portion 80 of the rod, one or more vanes or wings 83 are fixed on the rod, which act as stirrers to agitate the powder in the can and prevent it from packing when the rod is rotated. The 25 lower end of the rod may be positioned at any desired distance from the valve seat 81 to regulate the rate of escape of the powder from the can.

The nozzle 82 occupies a notch in the end 30 of the guard flange on the air nozzle 16 and extends into the path of the air current which issues from the air nozzle. The powder nozzle 82 is preferably located forwardly of the tip of the paint nozzle 38.

35 It will be understood that when ordinary paint, varnish or similar material is to be used, the powder can 69 will not be needed and may be removed from the brush by detaching the bracket 70 from the barrel 15.

40 The paint is then placed in the liquid paint container 50 or 51, and the brush operated in the manner hereinbefore described. It is possible to use bronze paint in this way by mixing the powder and liquid materials together and placing the mixture in the liquid paint container, but this is objectionable, because if the mixture is allowed to stand for any considerable length of time, it turns green or otherwise discolors, so that it is 45 unfit for use. To remedy this difficulty, I have provided two separate containers, one adapted to receive the bronze powder and the other an oil or other liquid suitable for use therewith. In the operation of this structure the air current issuing from the nozzle 16 draws the liquid paint material from the needle 37 and nozzle 38 and also draws the powdered material from the nozzle 82 and carries both materials together against the 55 article to be coated. I believe myself to be the first to provide separate containers for the paint ingredients in a pneumatic paint brush.

60 I claim as my invention:

65 1. A pneumatic paint brush having, in

combination, an air nozzle, a paint nozzle located outside of and at an angle to said air nozzle, the discharge orifice at the forward end of said paint nozzle opening toward the side adjacent to the discharge orifice of said air nozzle and being located in the path of the air current, and a member within said paint nozzle for controlling the discharge of paint. 70

2. A pneumatic paint brush having, in combination, a paint discharge structure comprising a tubular nozzle tapered at its forward end and a needle within said nozzle for controlling the discharge of paint therefrom, the discharge orifice at the forward end of said nozzle being oblique with respect to the axis of the nozzle, and an air nozzle separate from and extending at an angle to said paint discharge structure, said discharge orifice of the paint nozzle being disposed in a direction approaching a parallel 80 to the air current issuing from said air nozzle. 85

3. A pneumatic paint brush having, in combination, a body having an air nozzle on 90 its forward end, said nozzle being provided with a flared portion extending outwardly from the orifice in the nozzle, said flared portion being recessed to receive a paint nozzle, and a paint-discharge structure comprising a tubular nozzle having its forward 95 or discharge end occupying said recessed portion of the air nozzle, the discharge orifice at the forward end of the paint nozzle being disposed oblique to the axis of said 100 nozzle and in a direction approaching a parallel to the air current issuing from said air nozzle, and means in said paint nozzle to control the discharge of paint.

4. A pneumatic paint brush having, in 105 combination, an air nozzle, a paint nozzle located outside of and at an angle to the axis of said air nozzle, said paint nozzle being tapered at its forward end, the discharge orifice at the forward end of said paint nozzle being cut back from the extreme forward end on the side adjacent to the orifice of said air nozzle, whereby to obtain a more efficient relation of the current of air to said discharge orifice of the paint nozzle, and a 110 needle within said paint nozzle having a tapered end to close the latter for controlling the discharge of paint therefrom. 115

5. A pneumatic paint brush having, in combination, an air nozzle, a hollow needle located at one side of and disposed at an angle to the axis of said air nozzle, the forward end of said needle being tapered and the opening in said needle terminating at its forward end on said tapered portion, a 120 nozzle surrounding said needle and internally tapered at its forward end to fit the tapered end of said needle, said needle and said nozzle being movable with relation to each other to control the discharge of color, 125 130

- the edge of the discharge orifice of said nozzle being disposed obliquely to the axis of the nozzle and in a direction approximating a parallel to the path of the air current 5 issuing from said air nozzle.
6. A pneumatic paint brush having, in combination, a needle having a tapered forward end and having a longitudinal passageway therethrough terminating at its forward end on said tapered surface, a nozzle surrounding said needle and internally tapered at its forward end to fit against the tapered surface of the needle, the latter having an annular shoulder on said tapered section 10 between the ends thereof which provides a relatively sharp edge to contact with the internal tapered portion of said nozzle, whereby to effect a tight joint and prevent leakage.
- 15 7. A pneumatic paint brush having, in combination, a needle having a tapered forward end and having a longitudinal passageway therethrough terminating at its forward end on said tapered surface, a nozzle surrounding said needle and internally tapered at its forward end to fit against the tapered surface of the needle, the latter having on said tapered surface an annular depression providing two opposed annular 20 shoulders adapted to engage the interior of the tapered portion of said nozzle, whereby to effect a tight joint and prevent leakage.
- 25 8. A pneumatic paint brush, having in combination, a hollow needle having a tapered forward end, the passage in the needle terminating on said tapered surface, the needle having one or more annular grooves in its periphery behind said tapered surface, the grooves adapted to be filled with 30 hard oil, and a nozzle surrounding said needle and having a tapered forward end conforming to the tapered end of the needle.
- 35 9. A pneumatic paint brush having, in combination, a body having a perforated lug thereon, a sleeve passing through the perforation in said lug, a set-screw for fixing said sleeve therein, a second sleeve threaded on the forward end of the first sleeve ahead of said lug, a hollow needle fixed in the 40 first sleeve, a nozzle slidably mounted on said needle and positioned within the second sleeve, means tending to move said nozzle rearwardly, and means for moving said nozzle forwardly to permit the discharge of 45 paint material.
- 50 10. A pneumatic paint brush having, in combination, a body in the form of a barrel having an exterior perforated lug, a sleeve passing through the perforation in said lug, a second sleeve threaded on the forward end of the first sleeve ahead of said lug, a hollow needle secured in the forward end of the rear sleeve, a nozzle slidably surrounding said needle and located within the 55 forward sleeve, a coiled spring surrounding the nozzle within said forward sleeve and tending to move the nozzle rearwardly, the forward sleeve and said barrel having aligned slots therethrough, a rod passing through said slots, said nozzle having a recess in 70 which the forward end of said rod engages, and means for longitudinally moving said rod to slide said nozzle forwardly against the action of said spring.
- 75 11. A pneumatic paint brush having, in combination, a body having a downwardly extending handle by which the brush may be held like a pistol, a pair of triggers pivoted one ahead of the other and in front of said handle, and air discharge means and 80 paint discharge means connected to the respective triggers for operation thereby.
12. A pneumatic paint brush having, in combination, a body having a downwardly extending handle by which the brush may be held like a pistol, a pair of downwardly extending triggers pivoted one ahead of the other and in front of said handle, air discharge means connected to the forward trigger, and paint discharge means connected to 85 the rear trigger.
13. A pneumatic paint brush having, in combination, a body having a downwardly extending handle by which the brush may be held like a pistol, a pair of downwardly 90 extending triggers pivoted one ahead of the other and in front of said handle, air discharge means including a valve connected to the front trigger, paint discharge means connected to the rear trigger, said front trigger being arranged to engage and move said rear trigger, and the two triggers being spaced apart, whereby the front trigger may be moved rearwardly to unseat the air valve 95 before engaging the rear trigger.
- 100 14. A pneumatic paint brush having, in combination, a body, two finger levers mounted thereon, air discharge means operatively connected to one of said levers, paint discharge means operatively connected 105 to the other lever, the air lever being arranged to engage and move the paint lever, and the two levers being spaced apart, whereby the air lever may be moved to unseat the air discharge means before engaging 110 the paint lever.
15. A pneumatic paint brush having, in combination, a body, an air valve at the rear end of said body, paint discharge means at the forward end of the body, a pair of finger 115 levers mounted at the mid portion of the body, and rods connecting the respective levers with the air valve and the paint discharge means.
- 120 16. A pneumatic paint brush having, in combination, a body having a downwardly extending handle by which the brush may be held like a pistol, an air nozzle at the forward end of said body, a needle mounted on the body, a nozzle surrounding said needle 125 130

and slidable forwardly and back thereon to control the discharge of paint, a spring tending to move said nozzle rearwardly to cut off the flow of paint, a rod slidably mounted in the body and engaging the last mentioned nozzle, and a downwardly extending trigger lever pivoted in front of said handle and adapted to slide said rod forwardly.

17. A pneumatic paint brush having, in combination, a body, an air nozzle at the forward end of said body, an air valve at the rear end of said body, a paint nozzle adjacent to said air nozzle, a rod arranged to move said paint nozzle forwardly, a second rod arranged to move said air valve rearwardly to open the valve, and finger lever means for simultaneously sliding said rods in opposite directions.

18. A pneumatic paint brush having, in combination, a body having a downwardly extending handle by which the brush may be held like a pistol, an air valve at the rear end of said body, a pair of triggers pivoted forwardly of said handle, a rod connecting one of said triggers with said air valve, a paint nozzle at the forward end of said body, and a rod connecting the other one of said triggers with said paint nozzle.

19. A pneumatic paint brush having, in combination, a body having a downwardly extending handle by which the brush may be held like a pistol, an air nozzle at the forward end of said body, a needle mounted on the body, a nozzle surrounding said needle and slidably forwardly and back thereon to control the discharge of paint, a spring tending to move said nozzle rearwardly to cut off the flow of paint, a rod slidably mounted in the body and engaging the last mentioned nozzle, a downwardly extending trigger lever pivoted in front of said handle and adapted to slide said rod forwardly, and a screw threaded in the handle and adjustable to bear against said trigger and hold the rod in position to maintain the paint nozzle open.

20. A pneumatic paint brush having, in combination, an air nozzle, means for discharging liquid paint material into the path of air issuing from said nozzle, a container for powdered paint material, and a nozzle adapted to receive powder from said container and discharge the powder into the path of air issuing from said air nozzle, said liquid and said powder discharging means being capable of simultaneous or independent operation.

21. A pneumatic paint brush, having in combination, an air nozzle, means for feeding liquid paint material into the path of the air current issuing from said air nozzle, and means for feeding powdered paint material into the path of the air current in front of the point where the liquid paint material is discharged.

22. A pneumatic paint brush having, in combination, an air nozzle, a liquid paint discharging nozzle and a powdered paint discharging nozzle arranged to feed material into the path of air current issuing from said air nozzle.

23. A pneumatic paint brush having, in combination, an air nozzle, a liquid paint nozzle, and a powdered paint nozzle arranged to discharge material into the path of the air current issuing from said air nozzle, the liquid paint nozzle being positioned behind the powder paint nozzle.

24. A pneumatic paint brush having, in combination, an air nozzle, liquid paint material discharging means, a powdered paint container having a funnel-shape lower end, and having a nozzle at the tip of the funnel projecting into the path of the air current issuing from said air nozzle, both of said paint discharge means being capable of simultaneous or independent operation.

25. A pneumatic paint brush having, in combination, a body having an air nozzle at its forward end, a paint nozzle mounted outside of and at an angle to said body, a container for liquid paint material communicating with said paint nozzle, a bracket mounted on the body, a container for powdered paint material mounted in said bracket, and a nozzle communicating with the powder container, the latter nozzle and the paint nozzle projecting into the path of the air current issuing from said air nozzle.

26. A pneumatic paint brush having, in combination, an air nozzle, a container for powdered paint material, means therein for preventing packing of the material, and means located at the discharge end of the air nozzle and adapted to direct the material into the path of the air current issuing from said air nozzle.

27. A hand held pneumatic paint brush having, in combination, an air nozzle, a container for powdered paint material, a vertical axially disposed rod rotatably mounted in said container and having vanes thereon adapted to prevent packing of the material, and means to direct the material into the path of the air current.

28. A pneumatic paint brush having, in combination, a container for paint material, a cover therefor, a sleeve fixed to the inner side of said cover, a spider in which said sleeve is threaded, said spider being fixed in the lower portion of said container, an adjustably mounted rod passing through said sleeve, and agitating vanes on said rod.

29. A pneumatic paint brush having, in combination, a container for paint material, a cover therefor, a sleeve fixed to the inner side of said cover, a spider in which said sleeve is threaded, said spider being fixed in the lower portion of said container, an adjustably mounted rod passing through said

sleeve, the lower end of said rod providing a valve member, and an outlet nozzle for the container having a valve seat to coöperate with said valve member.

5 30. A pneumatic paint brush having, in combination, a body having an air nozzle at its forward end, a paint discharge structure mounted outside of and at an angle to said body, said structure comprising a sleeve 70
10 open at its rear end and exteriorly threaded adjacent to said rear end, a container for liquid paint material, a valved fitting secured to the bottom of the container and communicating therewith, an enlarged head 15 on said fitting arranged to engage in said sleeve, and a nut engaging said head and arranged to be turned onto the threaded rear end of said sleeve.

10 31. A pneumatic paint brush having, in combination, paint discharge means including a sleeve open at one end and exteriorly threaded adjacent to said end, a container for paint material, a conductor communicating with said container and having an enlarged 25 conical head on one end arranged to engage in the end of said sleeve, and a nut surrounding said conductor and engaging said head and adapted to be turned onto the threaded rear end of said sleeve to clamp the head 30 thereto.

32. A pneumatic paint brush having, in combination, a tubular body having an air nozzle on its forward end, a paint discharge structure mounted outside of and at an angle 35 to said air nozzle, said paint discharge structure comprising a needle and a nozzle slideable on the needle to control the discharge of paint, the body having a downwardly extending handle by which the brush may be 40 held like a pistol, a trigger pivoted in the body and extending downwardly in front of said handle, and a rod operatively associated at its rear end with said trigger and at its forward end with said paint nozzle, 45 whereby the nozzle may be projected forwardly by moving said trigger rearwardly.

33. A pneumatic paint brush having, in combination, a body provided with a downwardly extending handle by which the brush 50 may be held like a pistol, a paint discharge structure comprising two elements one of which is slideable with reference to the other, a trigger extending downwardly in front of said handle, a rod extending forwardly from 55 said trigger and operatively connecting the trigger to the said slideable element for moving the latter, said handle having a lateral opening therethrough, and a screw threaded in said handle and arranged to bear against 60 said trigger to limit rearward movement of said rod, the head of said screw occupying said opening in the handle to facilitate access to said head.

34. A pneumatic paint brush having, in combination, a body provided with a down- 65

wardly extending handle by which the brush may be held like a pistol, paint discharge means, a trigger depending from the body in front of said handle, means operatively connecting said trigger to the paint discharge means for opening the latter, and an adjustable screw threaded in said handle and arranged to hold said trigger in position to maintain the paint discharge means open. 70

35. A pneumatic paint brush having, in combination, a body having an air nozzle at its forward end, a liquid paint discharging structure adapted to discharge into the path of the air current and comprising two members relatively movable to control the 80 discharge of paint, and a powdered paint container rigidly mounted on the body and having its outlet positioned to direct powder into the path of the air current.

36. A pneumatic paint brush comprising, in combination, a unitary structure adapted to be held in the hand and having three nozzles for delivering air, liquid and powder, respectively, the air nozzle being located at the extreme forward end of the brush and 90 the other two nozzles being located to discharge liquid and powder into the path of the air current.

37. A pneumatic paint brush comprising, in combination, three separate nozzles arranged to deliver air, liquid and powder, respectively, at a common point located at the extreme forward end of the brush. 95

38. A pneumatic paint brush comprising, in combination, three nozzles arranged to deliver air, liquid and powder, respectively, said nozzles being positioned outside of and independent of each other and all being located at the extreme forward end of the brush. 100

39. A pneumatic paint brush having, in combination, an air nozzle, means for discharging liquid paint material into the path of air issuing from said nozzle, a container for powdered paint material, and a nozzle adapted to receive powder from said container, the tip of the latter nozzle being located at the extreme forward end of the air nozzle and adapted to discharge the powder into the air current. 110

40. A pneumatic paint brush having, in combination, an air nozzle, a liquid paint discharging structure located outside of and at an oblique angle to said air nozzle and arranged to discharge liquid paint into the 120 path of the air current, a powdered paint container mounted above the air nozzle in fixed relation thereto, and a nozzle communicating with said powdered paint container and adapted to direct the powdered 125 material into the path of the air current.

41. A pneumatic paint brush having, in combination, a body provided with an air nozzle at its forward end, a liquid paint discharge structure mounted on the body out- 130

side of and at an oblique angle to said air nozzle and arranged to discharge liquid paint into the path of the air current, and a powdered paint container mounted on said body 5 above said air nozzle, the outlet from said container being arranged to direct the powdered paint into the path of the air current,

In testimony whereof, I hereunto set my hand in the presence of two witnesses.

JENS A. PAASCHE.
